UNITED STATES PATENT OFFICE.

EDWARD G. WATKINS, OF GARDNER, MASSACHUSETTS.

DESIGN FOR CANE FABRIC.

SPECIFICATION forming part of Design No. 26,554, dated January 19, 1897.

Application filed December 11, 1896. Serial No. 615,413. Term of patent 7 years.

To all whom it may concern:

Be it known that I, EDWARD G. WATKINS, of Gardner, in the county of Worcester and State of Massachusetts, have invented and produced a new and original Design for Cane Fabric, of which the following is a specification.

Reference is to be had to the accompanying drawing, forming a part of this specification, which shows a piece of cane fabric with my design applied.

The leading feature of my design consists in the arrangement of parallel companion stripes *a a* and the intersecting companion stripes *b b*, all of a contrasting color from the body of the fabric and forming alternating figures of different widths, the stripes *a a* being interrupted, except at their intersection with the stripes *b b*, to show the body of the fabric as alternating marginal and central checks.

f represents a piece of cane fabric bearing my design, which consists of companion parallel stripes *a a* and the intersecting companion stripes *b b*, all of contrasting color from the body of the fabric, forming figures of different widths. The stripes *a a* are depressed, except at their intersection with the stripes *b b*, to show the body of the fabric in the form of marginal checks.

I claim—

The design for cane fabric, as herein shown and described.

In testimony whereof I have signed my name to this specification, in the presence of two subscribing witnesses, this 30th day of November, A. D. 1896.

EDWARD G. WATKINS.
